ABSTRACT

A safety device for a revolver wherein the cylinder is mounted on a pin which is selectively movable along its axis from a first fixed position at which the pin is free of engagement with the hammer to a second fixed position at which the pin engages the hammer to prevent it from reaching the firing position.

2 Claims, 3 Drawing Figures

PATENTED APR 16 1974

SHEET 2 OF 2

Fig. 3

SAFETY DEVICE FOR A CYLINDER REVOLVER

The invention relates to a safety for a cylinder revolver having a hammer.

In the field of revolvers there already exist safety features which prevent the accidental firing of shots, for instance in the case of the revolver being dropped. The known arrangements operate in such a manner that they limit the movement of the hammer. However, these arrangements are complicated or they operate in such a manner that they do not satisfy all safety requirements and the regulations of many countries.

The purpose of the invention is to provide for a cylinder revolver having a hammer, a safety which restricts the movement of the hammer and which can be utilized independently of the usual safeties and which is simpler than the known safeties as far as construction and handling are concerned.

The principle of the invention is that the axis pin of the cylinder is formed in such a way as to act as a safety pin. The cylinder axis pin is provided with two annular grooves. The axis pin is mounted so as to be axially movable, except when restricted in its movement by a latch pin mounted laterally with respect to the revolver frame. The latch pin is held in position by a coiled spring arrangement which maintains the latch pin in a position which engages either the first or the second annular groove of the axis pin, thus restricting axial movement of the axis pin.

The invention will be explained in detail by reference to the following drawings:

FIG. 1 shows, in cross section, the safety in its "Safe" position;

FIG. 2 shows the safety in the "Off" position, the revolver being ready for firing; and

FIG. 3 shows the safety after firing.

In the drawings the revolver is only demonstrated to such an extent as is necessary to understand the invention. The numeral 1 indicates the hammer which is under the pressure of the hammer spring 2 and which is restrained by the trigger 3. The sear tip 4 of trigger 3 is formed like a nose and cooperates with the full cock notch 5 and with two adjacent safety notches 6 and 6a on the hammer. The tip 4 of the trigger 3 engaging the safety notch 6a represents the traditional safety. A cylinder 7 is mounted inside frame 13 on a cylinder axis pin 8 which is rotatable and slideable. This cylinder axis pin 8 is characterized by two annular grooves, 10 and 11, with which a cylinder axis pin latch 9 cooperates. Numeral 12 indicates a shell which is hit by the firing pin 1a on the hammer at the moment of firing. Part 50 of the barrel is shown as 14.

The operation of the safety will now be described. The safety in its "Safe" position (FIG. 1) is arranged in such a way that the hammer 1 under pressure of the hammer spring 2 rests against the cylinder axis pin 8. In this position the hammer and the half cock notch 6 on the hammer 1 are held out of engagement with the sear tip 4 of the trigger 3.

It is the purpose of this invention to give the revolver a safety additional to the traditional one provided by the safety notch 6a. This is accomplished by the fact that the cylinder axis pin latch 9, which is retained in the annular groove 10 of the axis pin 8 by means of a spring, not shown in this picture, serves as a stop which prevents the axis pin 8 from sliding longitudinally. When the cylinder axis pin latch 9 is depressed it is moved laterally in such a way that it moves out of engagement with the annular groove 10 of the cylinder axis pin 8, thus releasing the pin so that it can be moved axially. As a consequence, while groove 10 is engaged, the hammer 1, and therefore the firing pin 1a, cannot possibly strike the cartridge 12. The result is a revolver absolutely safe against any uncontrolled activity, especially that caused by the revolver being dropped or by carelessness in operation of the hammer 1 or trigger 3.

The safety is put into "Off" position by bringing the hammer 1 backwards into shooting position (full cock position). This way the sear tip 4 of the trigger 3 engages the trigger notch 5 of the hammer 1. The cylinder axis pin latch 9 is depressed, thus permitting the cylinder axis pin 8 to be released allowing it to be moved axially until the pin latch 9 engages the groove 11. (See FIG. 2).

The cartridge is fired by pulling the trigger 3 releasing the hammer 1 which rotates forward under pressure of the hammer spring 2. The firing pin 1a strikes the shell 12 causing it to fire. (See FIG. 3).

The safety groove 10 should be arranged in such a manner that the safety becomes effective before the sear tip 4 of the trigger 3 engages the half cock safety notch 6 of the hammer 1 in order to avoid engagement of the trigger 3 while in safe position.

The above described feature has the advantage that, should the traditional safety fail, there is still an independent second safety available which restricts the hammer and consequently the firing pin 1a from striking the cartridge.

What is claimed is:

1. A safety device for a revolver of the type including a cylinder for supporting a cartridge to be fired, a trigger-actuated hammer and a firing pin associated with said hammer for firing said cartridge upon contacting the cartridge, the device comprising:

an axially movable pin upon which the cylinder is mounted; and
means for selectively securing said movable pin in a first axial position out of engagement with said hammer and in a second axial position for engaging the hammer so as to restrain the firing pin from contacting the cartridge.

2. A safety device as set forth in claim 1 wherein the pin in its second axial position engages the hammer so as to restrain it from contacting said trigger.
